Primary Examiner — Austin Murphy

(57) **CLAIM**

The ornamental design for mobile device, as shown and described.

DESCRIPTION

FIG. 1 is a bottom, front, right side perspective view of a mobile device according to my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, left side perspective view thereof.

The long dash-short dash broken lines represent boundaries of the claimed design and form no part thereof. All other broken lines represent portions of the mobile device that form no part of the claimed design.

1 Claim, 6 Drawing Sheets
